(57) **CLAIM**

The ornamental design for a lottery ticket dispenser, as shown and described.

DESCRIPTION

FIG. 1 is a perspective view of a first embodiment of a lottery ticket dispenser according to our new design.

FIG. 2 is a front elevational view of the embodiment of FIG. 1.

FIG. 3 is a right side elevational view of the embodiment of FIG. 1 with the left side being a mirror image thereof.

FIG. 4 is a rear view thereof.

FIG. 5 is a top view thereof.

FIG. 6 is a bottom view thereof.

FIG. 7 is a front view of a second embodiment of a lottery ticket dispenser according to our new design and the top and bottom views being the same as FIGS. 5 and 6, respectively.

FIG. 8 is a right side view of the embodiment of FIG. 7 with the left side of the dispenser being a mirror image thereof.

FIG. 9 is a rear view thereof.

FIG. 10 is a front view of a third embodiment of a lottery ticket dispenser according to our new design and the top and bottom views being the same as FIGS. 5 and 6, respectively.

FIG. 11 is a right side view of the embodiment of FIG. 10 with the left side of the dispenser being a mirror image thereof.

FIG. 12 is a rear view thereof.

FIG. 13 is a front view of a fourth embodiment of a lottery ticket dispenser according to our new design and the top and bottom views being the same as FIGS. 5 and 6, respectively.

FIG. 14 is a left side view of the embodiment of FIG. 13 with the right side of the dispenser being a mirror image thereof.

FIG. 15 is a rear view thereof.

FIG. 16 is a front view of a fifth embodiment of a lottery ticket dispenser according to our new design and the top and bottom views being the same as FIGS. 5 and 6, respectively.

FIG. 17 is a left side view of the embodiment of FIG. 16 with the right side of the dispenser being a mirror image thereof; and,

FIG. 18 is a rear view thereof.
